UNITED STATES PATENT OFFICE.

ANTONIO GALANTE, OF MEDFORD, MASSACHUSETTS.

APPARATUS FOR MOLDING ARTIFICIAL STONE.

Application filed August 25, 1924. Serial No. 733,973.

The present invention relates to apparatus adapted for use in molding artificial stone. Molds of wood, plaster of Paris, and the like, were formerly used and are subject to the common fault that the liquid stone must remain in the mold until it is set, thereby causing delay before the mold can be used again. Moreover, wood molds are quickly rendered useless from warping from contact with the cementitious material.

The object of my invention is to improve upon the prior art, and with this end in view, a feature of my invention is the formation of upstanding walls by the use of any molding material adapted to said formation in connection with the construction of my improved pattern and in using the space between said walls for the reception and hardening of the cementitious material.

This and such other objects as may hereinafter appear are attained by the devices illustrated in the accompanying drawings showing the preferred form of my invention, in which Fig. 1 is a perspective view of a split bottomless pattern; Fig. 2, a partial end elevation of the same; Fig. 3, a detail of the tongue-and-groove sliding engagement between the sections of the pattern; Fig. 4, a longitudinal view showing the pattern in place and the molding material tamped within and without the same; Fig. 5, a longitudinal section showing the pattern withdrawn and the cementitious material poured into the mold formed thereby; Fig. 6, a cross-section showing the pattern withdrawn and the cementitious material poured into the mold formed thereby; Fig. 7, a cross-section showing the first section partially removed; Fig. 8, shows a core, 22^a.

Similar letters and numerals refer to similar parts throughout the several views.

In the drawings, the stop *w* shown in Fig. 2 and Fig. 7, adapted to engage the recess *w'* shown in Fig. 7, prevents the section 2^a from slipping on the section 2^b.

Fig. 3 shows the dovetailed tongue *t* of section 2^b engaging the groove *g* of section 2^a.

In Fig. 4 the tongue-and-groove connection is represented by 2^{a-b}.

I am aware that molding materials adapted to form self-sustaining walls have been known in the art and have been employed to some extent in the molding of artificial stone, but my improved apparatus is novel

and shows a decided advance over the prior art. In connection with my improved device, any molding material may be employed, adapted to take a true impression of the pattern without sticking, when packed closely within and without the same, and to leave self-sustaining walls when the pattern is removed.

My invention is simple, inexpensive, and of great commercial value.

In carrying out my invention, the split bottomless pattern is placed on a bed 4 of a molding material adapted to form self-sustaining walls as shown in Fig. 2, material of the same kind is then rammed compactly to fill the interior of the pattern up to the line 6-6 and is rammed against the outer walls up to the line 12-12 as shown in Figs. 2 and 4, the surfaces 6-6 and 12-12 being leveled by a straight edge or other suitable means.

Section 2^a is first removed by the handle 13. The two sections are so proportioned that the parting plane designated by line *y-y* along which section 2^a slides is kept parallel with *x-x* in the plane of the inclined wall effecting the removal of 2^a without scratching or in any way impairing the contour of the inclined mold walls. If it is desired to form holes for straining and drainage purposes, the core 22^a may be placed in the position shown in Fig. 4. The section 2^b may now be removed by its handle 13, forming a complete mold into which the cementitious material is to be poured. To mold the bottom of the sink-section the core box 26 is used which may be filled with sand, concrete or the like, to give it sufficient weight to maintain its positioning, said positioning being effected by cleats 28. Reinforcing rods 33 are embedded in the sink-section to give it strength. In Fig. 3 are shown two sections 2^a and 2^b engaging each other by a tongue *g* and groove *t* in which *t* is dovetailed into *g*.

It is to be observed that the interior walls of the pattern are cut out so as to leave the space between 6-6 and 12-12 as shown in Fig. 4 for the further reception of the cementitious material used in molding the bottom of the article produced, said article being molded in an inverted position as shown in Figs. 5 and 6.

It is to be noted that I do not limit my invention to the precise steps, means, and

objects hereinbefore set forth, but the same may be varied to suit the various forms of molding stoneware without departing from the spirit and scope of my invention.

5 I claim:

1. A split bottomless pattern comprising a section slidably engaging a second section; a stop integral with the first section adapted to engage a recess in the second section; 10 means for forming holes for straining and drainage purposes; means for successively raising the sections, said sections engaging each other so as to co-operate as a unit while a molding material capable of forming self-sustaining walls is rammed compactly so as to fill the interior of said pattern up to the line 6—6 and around the exterior of the pattern up to the line 12—12, the interior walls of the pattern being cut out so as to form 15 the additional molding space 6—12 needed for the formation of the bottom of the article produced, the mold formed by the upstanding walls of the molding material when the pattern is withdrawn with the above addition forming the complete mold the reception of the cementitious material during the 20 removal of the first section, the parting plane remaining substantially parallel with 25

the oblique side of the pattern so as to leave intact the inclined molding space. 30

2. A split bottomless pattern comprising a section slidably engaging a second section; a stop integral with the first section adapted to engage a recess in the second section; 35 means for successively raising the sections, said sections engaging each other so as to co-operate as a unit while a molding material capable of forming self-sustaining walls is rammed compactly so as to fill the interior of said pattern up to the line 6—6 and 40 around the exterior of the pattern up to the line 12—12, the interior walls of the pattern being cut out so as to form the additional molding space 6—12 needed for the formation of the bottom of the article produced, the mold formed by the upstanding walls of the molding material when the pattern is withdrawn with the above addition forming the complete mold the reception of the cementitious material during the 45 removal of the first section, the parting plane remaining substantially parallel with the oblique side of the pattern so as to leave intact the inclined molding space. 50

In testimony whereof I affix my signature.
ANTONIO GALANTE.
